UNITED STATES PATENT OFFICE

LOUIS A. M. PHELAN, OF ELKHART, INDIANA, ASSIGNOR, BY MESNE ASSIGNMENTS,
TO TIME-O-STAT CONTROLS COMPANY, OF ELKHART, INDIANA, A CORPORATION
OF MARYLAND

ELECTRIC SWITCH

Application filed December 22, 1926, Serial No. 156,344. Renewed January 6, 1930.

This invention relates to electric switches and it has special reference to improvements in electrical contactors wherein the conducting terminals or electrodes are enclosed in a sealed container, which latter also contains a compact and coherent body of current-conducting fluid, such as mercury, through the medium of which, said electrodes are brought into electrical current conducting relation with one another.

One of the objects of this invention is to provide an electric switch, as indicated above, which is capable of opening and closing an electrical circuit an extraordinary number of times without undergoing substantial deterioration or disintegration.

A further object of this invention is to provide an electrical contactor switch in which the electrodes are made of different materials in order to control the movement of the body of the current-conducting fluid, such as mercury, under certain predetermined conditions.

A still further object of this invention is to provide an electric contactor as referred to above in which one electrode is so constructed, and the materials comprising that electrode are so selected, that a film of mercury will adhere to said electrode and cause a make and break to occur between two mercury bodies, that is to say, the main body of mercury and the film adhering to the electrode.

Further objects will be apparent from the description and drawings forming a part of this specification to which reference may now be had for a more complete understanding of the characteristic features of this invention, in which drawings:

Figure 1 is a view, partially in section and partially in elevation, of a contactor embodying this invention in which the electrodes are disposed in one end of the container;

Fig. 2 is a view partially in section of one of the electrodes comprised in Fig. 1;

Fig. 3 is a view, partially in section of a modified form of one of the electrodes comprised in Fig. 1;

Fig. 4 is a diagrammatic view illustrating the method in which a body of mercury in a

contactor breaks at an electrode having a lower rounded end; and

Fig. 5 is a diagrammatic view illustrating the method in which a body of mercury in a contactor may break from an electrode which is provided with a core made of a material to which the mercury adheres with some tenacity.

Referring more particularly to the drawings, the contactor comprises a container 10 in which two spaced electrodes 11 and 12 are hermetically sealed. The electrodes 11 and 12 are shown as disposed adjacent one end of the tube, and fixed to supporting members 13 and 14. The supporting members are, in turn, connected to leading-in-wires 15 and 16 respectively, which provide means for electrically connecting the electrodes 11 and 12 to their respective accessible terminals 17 and 18. A body of mercury 19 is also disposed within the container 10 and serves to bridge the electrodes 11 and 12. Thus, under certain conditions, such as by tilting the contactor, an electrical circuit is established through the contactor.

The container 10 may be made of glass of the quality usually employed in manufacturing incandescent lamp bulbs, etc., or it may be made of either pyrex or boro-silicate glass. When the container is made of glass such as is usually employed for bulbs and the like, the leading-in-wires 15 and 16 are preferably made of a suitable wire, that is, one that will insure the retention of permanent hermetic seals for the container; this latter being necessary, for instance, when the seals become heated, or when substantially high currents are handled by the contactor.

A well known sealing-in-wire is known in the trade as "Dumet" which consists of an exterior copper coating over a nickel-iron alloy. If, however, the container be made of pyrex or boro-silicate glass, the leading-in-wires are preferably made of tungsten.

The supporting members 13 and 14 for the electrodes are connected to their special leading-in-wires 6 and 7 by means of welding, or any other desirable method, and said connections are then embedded in glass shanks 20 and 20^a in order to prevent exposure of the

leading-in-wires situated in the interior of the container. These supporting members may be made of a non-deteriorating or inert metal such as iron.

- 5 In order to maintain the interior of the container 10 inert to the material entering into the construction thereof, the atmospheric air is evacuated from the container to a substantially high degree and is then filled with 70
10 an inert gas, such as hydrogen, to a pressure approximating atmospheric pressure. By this means of filling the container with an inert gas, and further, by properly selecting the materials exposed within the interior of 75
15 the container, deterioration and disintegration of the contactor are greatly reduced when said contactor is subjected to severe service conditions.

20 The electrodes 11 and 12 are of different construction. The electrode 12 is made of any suitable material preferably of iron-chromium alloy or iron alone, while the electrode 11 may be made of monel or, as illustrated in Fig. 2 of the drawing, may comprise a main body portion 21 which may be 80
25 made of iron or an iron chromium alloy having a central core 22 made of monel.

20 When the electrode 11 consists of a plurality of portions all made of different materials, the body portion 21 is preferably 85
30 made of a metal such as an iron chromium alloy or chromium steel alloy which does not disintegrate or deteriorate rapidly when subjected to an electric arc, however, this portion 90
35 may also be made of tungsten, molybdenum, or the like. When the said body portion 21 is made of the materials mentioned above it does not readily amalgamate with or become wetted by the mercury and, therefore, 95
40 only a small film, if any, of mercury adheres to the body portion 21.

40 The core 22, which is made of Monel metal, constitutes a metal that readily amalgamates or wets with the mercury so that when the 100
45 meniscus of mercury recedes from the electrode, a small drop or body 23 of mercury will adhere to the core portion 22. This body of mercury 23 adheres tenaciously to the core because of the amalgamation therewith and 105
50 the mercury. This insures, in subsequent breaks between the electrodes and the meniscus of mercury, that the breaks in the electric current or the arcs will occur between the main body of mercury in the contactor and 110
55 the film or drop 23 which adheres to the electrode core 51.

55 In a modified form, as shown in Fig. 3, the main body portion 24 may preferably be made of an iron chromium alloy or of any of 115
60 the metals mentioned above, and the core 25 may be made of Monel metal to which mercury will readily adhere. The lower portion of the electrode is rounded off as shown at 120
65 26 in order to prevent the formation of any sharp corners or edges which would tend to

deteriorate and disintegrate in the event that the electric arcs occurred adjacent to them. A body of mercury 27 will adhere to the monel core 25 for the same reason, as illustrated in Fig. 2. The concavity or recessed portion 28 of the electrode 24 tends to cause a body of mercury 27 to adhere with a high degree of tenacity to the core 25. In both the electrodes of Figs. 2 and 3 the supporting members may be inserted into openings 29 and 30 respectively.

75 As concerns the action of the meniscus mercury in relation to the electrodes where the electric arcs are broken when the contactor is moved to open circuit position, reference 80 may be had first to Fig. 4 wherein an electrode 31 having a lower rounded end is shown in contact with a body of mercury 32, the mercury being shown as receding from said electrode just prior to the breaking of the circuit. If the entire body of the electrode 31 is made of iron or an iron chromium alloy, the mercury film formed thereupon is insufficient to cause any substantial or effective portion of the mercury body 32 to adhere thereto in opposition to the cohering force 85 which exists in situ in the mass of the meniscus of mercury 31. As the circuit is being 90 broken, a very small thread of mercury 33 connects the main body of mercury 32 to the electrode 31, and when this thread breaks the direct and intimate contact between the electrode 31 and the mercury 32, an arc will occur at the surface of said electrode and, if 95 the arc persists for any period of time, it will 100 cause disintegration of the electrode. Moreover, the body of mercury 32, after breaking the thread 33 and disconnecting itself completely from the electrode 31, may not possess sufficient momentum to insure that at 105 all times the mercury body will flow rapidly away from the electrode 31.

110 Referring to Fig. 5, the electrode 34 is shown as being provided with a core 35, similar to the electrode shown in Fig. 2. As the body of mercury 36 flows away from said electrode, a substantial portion of mercury, indicated at 37, will adhere tenaciously to the bottom of the core 35. The mercury will be stretched as indicated at 38 to a narrow cross-sectional area at a substantial distance from the electrode 34. The force of adherence between the core 35 and the body of mercury 37 is sufficient to cause the body of mercury 36, on receding further from the electrode 34, 115 to break at the narrow cross-section portion 38. The meniscus of mercury 36 will then flow rapidly away from the electrode 34 after 120 said rupture occurs. In this manner the arc occurs between two bodies of mercury and not 125 at the surface of the electrode 62. The electrode is thus protected from disintegration which would otherwise occur if electric arcs were brought into intimate contact therewith.

130 It will be apparent that the action of the

meniscus with respect to the electrode illustrated in Fig. 2 and described above would be just as applicable to the electrode illustrated in Fig. 3, that is, a substantial portion of mercury would adhere tenaciously to the bottom of the core 25 and the body of mercury in receding from the electrode 24 would break at a substantial distance from said electrode, thereby arcing between two bodies of mercury and not at the surface of the electrode 24.

The body of mercury 19 in the container 10 which serves to bridge the electrodes 11 and 12 may be chemically pure, in fact in many circumstances this is desirable. However, in order to increase the mobility of the mercury to effect a rapid flow back and forth in the container, a small quantity of a solution of hydrocyanic acid, or other compounds of cyanide, may be mixed with the mercury. This process of treating mercury renders the same highly mobile, without affecting its electrical conducting properties or causing its deterioration or disintegration when embodied in a contactor, and is equally as desirable under other and different circumstances.

As has been hereinbefore stated, it is preferable to have the electrodes 11 and 12 of different construction, the electrode 12 being made of any suitable material, preferably an iron chromium alloy or iron alone, while, the electrode 11 comprises a main body portion which may also be made of iron or an iron chromium alloy, said body portion having a core of Monel metal. Since the monel core of the electrode 11 readily amalgamates or wets with mercury, on tilting the contactor, the body of mercury 19 will adhere to said electrode 11 until the proper angular displacement of the contactor is effected whereafter the body of mercury will snap away from the electrode 11. As the electrode 12 is of such material that it substantially precludes mercury therefrom, the body of mercury 19 is not obstructed in its rapid flow to and away from the electrode 11.

From the foregoing, the advantages residing in the electrodes will be apparent since a substantial film of mercury will adhere to either of the electrodes illustrated in Figs. 2 and 3 by reason of the monel core portions and subsequent breaks of the arc, whereby the breaks will occur between two mercury bodies, namely, the body of mercury adhering to the electrode and the main body of mercury 19. Electrodes constructed in accordance with those shown in Figs. 2 and 3, and in the manner hereinbefore described, are substantially non-disintegrating and non-deteriorating since, as pointed out, the electric breaks and makes occur between two mercury bodies which are highly satisfactory electrical contact making mediums.

The material monel is well known in the art and its composition is also well known in

the art. For further information as to this material and its physical properties, reference may be had to pages 1935 and 1936 of the publication entitled "Handbook for Electrical Engineers" by Harold Pender, editor-in-chief, and published by John Wiley & Sons, Inc., and copyrighted in 1914, as well as to pages 531 and 532, inclusive of a publication entitled "Kents Mechanical Engineers' Handbook", 10th edition, 1925, published by John Wiley & Sons, Inc. That monel is a well known material appears from the advertisement on page 91 of the October 20, 1928 issue of the publication entitled "The Literary Digest" 70

While but two specific embodiments of this invention have been shown and described, it is to be understood that the invention is not to be limited to these specific disclosures since various modifications will be apparent to those skilled in the art without departing from the spirit and scope of this invention, and, therefore, this invention is to be limited only by the appended claims and the prior art. 80

I claim:

1. A contactor comprising spaced cooperating electrodes one of which is substantially non-amalgamating with mercury and the other of which is made of monel. 95

2. A contactor comprising cooperating spaced electrodes one of which is made of a chromium iron alloy and the other of which is made of monel. 100

3. A contactor comprising an elongated hermetically sealed container, cooperating electrodes spaced longitudinally of the container, and a movable body of mercury contained therein, the electrode immediately adjacent to the end of said container being of Monel metal to which a mercury film readily adheres, and the other electrode being made of a material substantially non-amalgamating with said mercury. 105

4. A contactor comprising an elongated hermetically sealed container, cooperating electrodes spaced longitudinally of the container, and a movable meniscus of mercury contained therein, the electrode immediately adjacent to the end of said container being of Monel metal to which a mercury film readily adheres, and the other electrode being made of a chromium iron alloy. 110

In witness whereof, I have hereunto subscribed my name. 115

LOUIS A. M. PHELAN. 120
